By Richard B. Oliver Attorney

UNITED STATES PATENT OFFICE.

JOHN FAUTH, OF WYANDOTTE, MICHIGAN.

WIRE STRETCHER.

Application filed September 15, 1924. Serial No. 737,935.

To all whom it may concern:

Be it known that I, JOHN FAUTH, a citizen of the United States, residing at Wyandotte, in the county of Wayne and State of Michigan, have invented certain new and useful Improvements in Wire Stretchers, of which the following is a specification.

This invention appertains to a combined device for stretching wire and for pulling 10 out tree stumps, old fence posts and the like.

The primary object of the invention is to provide a wire stretcher having a novel frame for receiving the wire pulling element, 15 whereby the necessity of providing a rigid fence post or the like to hitch the pulling element to is eliminated.

Another object of the invention is the provision of a combined wire stretcher and fence post puller embodying a novel rigid frame and novel means mounted upon the frame for receiving the hoisting or pulling 20 rope.

A further object of the invention is the provision of novel guide and supporting pulleys for the hoisting or pulling rope and novel means for adjusting the pulleys on the frame to permit the expeditious stretching of wire arranged at different heights.

A further object of the invention is the provision of a novel frame for the combined wire stretcher and fence post puller which can be readily knocked down or collapsed so as to occupy a minimum amount of space 30 during transit or storage.

A still further object of the invention is to provide an improved device of the above character which will be durable and efficient in use, one that will be simple and easy to 40 manufacture and one which can be placed upon the market at a reasonable cost.

With these and other objects in view, the invention consists in the novel construction, arrangement and formation of parts, as will 45 be hereinafter more specifically described, claimed, and illustrated in the accompanying drawings, in which drawings,

Figure 1 is a side elevation of the improved device,

Figure 2 is a section taken on the line 2—2 of Figure 1 looking in the direction of the arrows and illustrating the novel arch for supporting the hoisting or pull cable,

Figure 3 is a horizontal section taken on 55 the line 3—3 of Figure 1 looking in the di-

rection of the arrows and illustrating the novel supporting base and seat,

Figure 4 is a vertical section taken through the frame on the line 4—4 of Figure 1 illustrating the supporting standards for the 60 front of the frame,

Figure 5 is a vertical section taken on the line 5—5 of Figure 1 showing the rear supporting standards on the frame,

Figure 6 is a top plan view of the wire 65 pulling element which can be used in connection with the improved device.

Referring to the drawings in detail, wherein similar reference characters designate corresponding parts throughout the several 70 views the letter A generally indicates the improved device, which comprises a novel frame B and a wire pulling element C.

The frame B includes a pair of spaced parallel upright rear standards 10 and 11 75 and a pair of diverged rearwardly inclined front standards 12 and 13. The lower terminals of the rear standards 10 and 11 are adapted to be fitted on or secured to a horse shoe shaped base plate 15 and the frame is 80 braced by a pair of forwardly inclined converging brace beams or standards 16. The lower terminals of these brace beams or standards 16 are fitted on or secured to the inner terminals of the base plate 15 and the 85 lower face of the base plate directly below the standards 10 and 11 is provided with penetrating ground engaging anchors or teeth 17.

The lower terminals of the standards 12 90 and 13 are provided with flat plates which form feet for engaging the ground and these feet are provided with depending penetrating spikes 19.

The upper terminals of the standards 10 95 and 11, 12 and 13 and 16 support the arch 20 which embodies a pair of spaced parallel bars 21. As shown the upper ends of the rear pair of standards 10 and 11 are bolted to the rear end of the arch 20 while the pair of standards 16 and the pair of standards 12 and 13 are bolted at the same point to the forward end of the arch.

The standards can be constructed from any desired material having the necessary 105 tensile strength such as tubing or the like, but as shown these standards are formed by flat bars of the desired gauge.

The opposite terminals of the arch 20 support guide pulleys 22 and 23 respectively 110

and the intermediate portion of the arch has disposed between the straps 21 thereof idle pulleys 24.

As clearly shown in Figures 1 and 5 of the drawing the standards 10 and 11 are provided with a series of spaced pairs of supporting hooks 25 for receiving the shaft 26 of a guide pulley 27 and it is to be understood that this pulley can be supported 10 by any desired pair of hooks 25.

The inclined standards 16 are provided with pairs of transversely aligned openings 28 for the reception of a guide pulley 29 and it is obvious that by means of these pairs 15 of openings that the pulley can be raised or lowered as desired.

A supporting bar 30 is arranged between the standards 12 and 13 and secured at its upper end to the said standards. The supporting bar 30 adjacent to its lower end is secured to the central portion of a transversely extending brace bar 31 which is secured to the standards.

A plurality of spaced hooks 32 are secured to the bar for a purpose, which will be hereinafter more fully described.

A windlass 33 is carried by the rear pair of standards 10 and 11 and this windlass embodies a drum 34 secured in any preferred way to a supporting shaft 35 which is mounted in bearings carried by the said standards 10 and 11. One end of the shaft 35 is provided with a relatively large gear wheel 36 which meshes with a small drive gear wheel 37 carried by the stub shaft 38. This stub shaft 38 is rotatably supported by the standard 11 and is provided with a hand crank 49. The shaft can be held against rotation in one direction by the use 40 of a suitable ratchet wheel and dog.

The wire puller C, which is associated with the frame B, embodies a triangular shaped base plate 40 which carries a pair of serrated cam rollers 41 which constitute the wire gripping means. The apex portion of the triangular shaped plate 40 carries a guide pulley 42 the purpose of which will be hereinafter more fully described.

When it is desired to stretch wire with 50 the improved device a pull cable 43 is used and one end of the cable is hitched to and wound about the drum 34 of the windlass 33. The opposite end of the cable is provided with an eye 44 which is placed over 55 any one of the hooks 32. The intermediate portion of the pull cable 43 is first trained over the guide pulley 22, the idle pulleys 24 and the guide pulley 23 of the supporting arch 20 after which the cable is trained 60 about the guide pulleys 27 and 29 which can be held in any preferred adjusted position on the standards 10 and 11 and the standards 16 respectively. The cable is now brought downwardly and wound about a 65 guide pulley 44 carried by the bar 30 and

then around the pulley 42 of the pulley element C.

The wire to be stretched is now placed between the serrated rollers 41 and by winding up the cable 43 on the drum 34 the wire 70 can be effectively stretched. After the wire has been drawn to the desired tension, retrograde movement of the drum is prevented by the use of the dog or ratchet wheel here- 75 tofore described.

When the improved device is to be used for pulling old fence posts, stumps and the like from the ground the frame B is placed directly over the fence post or stump to be pulled and a hoist cable is utilized instead 80 of the pull cable. In this instance the hoist cable is left depending from the pulley 29 and is not brought around the guide pulley 45 of the bar 30 and the pulling element 85 C is entirely eliminated. The free end of the cable can either be tied around the stump or post to be pulled or the free end of the cable can be provided with an auger or the like which can be threaded into the 90 stump or post.

The drum 34 is operated in the same manner for pulling fence posts as for pulling or stretching wire.

From the foregoing description, it can be seen that I have provided a novel implement 95 of a substantial and durable construction which can be used both for stretching wire and for pulling stumps and the like from the ground.

Changes as to details may be made without departing from the spirit or the scope of this invention, but:

What I claim as new is:

1. In a device for the purpose specified, a frame including a pair of rear standards, a pair of rearwardly inclined front standards, a pair of diagonally extending brace standards, a supporting arch secured to the upper terminals of the standards, anchors associated with the lower terminals of the standards for engaging the ground, guide and idle pulleys carried by the arch, a guide pulley adjustably associated with the rear pair of standards, a guide pulley adjustably associated with the guide and brace standards, a cable trained over said pulleys, and a windlass mechanism carried by the rear standards for winding up the said cable.

2. In a device of the class described, a frame including a pair of rear standards, a pair of rearwardly inclined front standards, a pair of diagonally extending brace standards, a supporting arch secured to the upper terminals of the standards, ground engaging anchors associated with the lower terminals of the standards, a bar carried by and disposed between the front pair of standards having a plurality of equi-distantly spaced hooks carried by said bar, pair of spaced hooks carried by the rear pair 130

of standards, a plurality of spaced openings carried by the brace standards, guide and idle pulleys associated with the arch, guide pulley adapted to be associated with 5 any of the pairs of hooks carried by the rear standards, a second guide pulley embodying a shaft adapted to be fitted in any of the openings in the brace standards, a third guide pulley secured to the bar, a wire 10 pulling element embodying a wire clamp and a guide pulley, a pulling cable trained about said guide pulley, a windlass carried by the rear standard around which one end of the cable is adapted to be wound, and 15 an eye carried by the other end of the cable for engaging any one of the hooks carried by said bar.

3. In a device of the class described, a frame including a pair of spaced parallel 20 upright rear standards, a pair of rearwardly inclined converging front standards, a

pair of diagonally extending brace standards converging toward their upper ends, a supporting arch, means connecting the upper terminals of the rear standards, to 25 the arch adjacent to the rear terminals thereof, means securing the upper terminals of the front standards and the brace standards to the forward end of the arch, a U-shaped base plate having a plurality of an- 30 anchor spikes carried by the lower face thereof, the lower terminals of the rear and brace standards being fitted upon said plates flat feet carried by the lower ends of the front standards and ground penetrating spikes 35 carried by said feet.

In testimony whereof I affix my signature in the presence of two witnesses.

JOHN FAUTH.
